JOHN M. ROHLFING, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

RAILWAY-CAR END CONSTRUCTION.

1,074,746.

Specification of Letters Patent.

Patented Oct. 7, 1913.

Application filed January 14, 1913. Serial No. 742,001.

To all whom it may concern:

Be it known that I, JOHN M. ROHLFING, a citizen of the United States, residing at the city of St. Louis, State of Missouri, have 5 invented a certain new and useful Improvement in Railway-Car End Construction, of which the following is a full, clear, and exact description, such as will enable others skilled in the art to which it appertains to 10 make and use the same, reference being had to the accompanying drawings, forming part of this specification, in which—

Figure 1 is an elevational view of a car end of my improved construction. Fig. 2 15 is a vertical section taken on the line 2—2 of Fig. 1. Fig. 3 is a top plan view of the car end. Fig. 4 is a horizontal section taken on the line 4—4 of Fig. 1. Fig. 5 is a horizontal section taken on the line 5—5 of 20 Fig. 1.

My invention relates generally to railway car end construction, and more particularly to the construction of the car end wall or plate.

25 In railway cars, and particularly those designed for and used in freight service, the end portions of the car bodies, and particularly the end walls, are subjected to severe stresses and strains not only because 30 of the sudden starting and stopping of the cars and the consequent vibration, but by reason of the shifting of the load or contents of the car while the latter is in transit, and also by reason of blows or shocks which 35 the end wall may receive while the car is in service.

I propose to construct a car end from a single piece of material, such as sheet metal, the same being provided with ribs or corrugations arranged so as to reinforce and stiffen the plate to a maximum degree so that in service it will effectively resist all 40 stresses and strains it may receive as the result of vibration, internally and externally 45 applied blows or from collisions.

The principal object of my invention is to construct the car end in a single piece, preferably a section of sheet metal, to reinforce and stiffen the same by means of ribs or

corrugations pressed in the sheet metal and 50 to arrange on the inside of the sheet metal plate reinforcing strips which are positioned directly over the ribs or corrugations, thus providing an extremely simple, inexpensive construction which will materially increase 55 the strength and rigidity of the end portion of the car body.

To the above purposes, my invention consists in certain novel features of construction and arrangement of parts hereinafter 60 more fully described and claimed.

In the construction of my improved car end as shown, 10 designates a plate of sheet metal of such size and contour as to form the entire end wall of the car body, and formed 65 in said plate on opposite sides and at equal distances from the center thereof are vertically disposed stiffening ribs or corrugations 11 which extend from the bottom of the plate to points near the top thereof. These 70 ribs or corrugations are preferably deepest at their lower portions and gradually decrease in depth toward their outer ends.

Formed in the plate 10 to the sides of the ribs or corrugations 11 and extending from 75 the lower ends thereof upwardly and outwardly toward the upper corners of the plate are diagonally disposed ribs or corrugations 12 which gradually decrease in depth toward their upper ends. The lower 80 ends of the corresponding pairs of corrugations 11 and 12 unite at the lower portion of the plate 10 to form short vertically disposed ribs or corrugations 13.

Positioned against the rear or inner face 85 of the plate 10 and arranged immediately over the ribs or corrugations 11, 12 and 13, are metal plates 14, the same being attached to the plate 10 by means of rivets or like fastening devices, the same being arranged 90 in rows along the sides of the ribs or corrugations. This construction ties the plate together across the ribs or corrugations pressed therein and forms a very strong and rigid construction which is particularly effective 95 in resisting all stresses and strains imparted to the end plate and which may tend to distort the same.

- The upper edge of the plate 10 is formed so as to conform with the shape of the car roof, and formed in the upper portion of said plate directly above the upper ends or 5 corrugations 11 is a horizontally disposed rib or corrugation 15 which is preferably deepest at its central portion and which gradually decreases in depth and width toward its ends. Riveted to the lower portion 10 of the plate 10 are the vertical legs of a series of angle strips 16, the horizontal legs of which extend forward and are adapted to engage directly upon the underframe or end sill to which the car end is fixed.
- 15 The lower ends of the plates 14 which are located over the short vertically disposed ribs or corrugations 13 are bent forwardly to form flanges 17 which coincide with the horizontal legs of the angle strips 16 and rest 20 directly upon the underframe or end sill to which my improved car end is fixed.
- A car end of my improved construction is comparatively simple, does away with the expense incident to the time and labor involved in forming a car end of built-up construction, and by providing the corrugations in the plate and reinforcing the same with the plates arranged over said corrugations, an exceptionally strong and rigid car 25 end is provided which is effective in resisting externally applied crushing strains such as may be received in collisions, or internally applied stresses resulting from shifting loads.
- 30 My improved end plate can be readily combined with car bodies of ordinary construction and when used in connection therewith, the impact and stresses produced by blows received by the end plate in service 35 are transmitted directly to the strongest parts of the car body, viz: the corners thereof.
- It will be readily understood that minor changes in the size, form and construction of 40 the various parts of my improved car end can be made and substituted for those herein shown and described without departing from the spirit of my invention, the scope of which is set forth in the appended claims.
- 45 I claim:
1. A car end constructed of pairs of sheet metal having formed therein a series of stiffening ribs or corrugations, extending across the sheet of metal, the members of 50 each pair being united at one end and reinforcing plates fixed to the sheet metal plate over said ribs or corrugations.
  2. A car end constructed of a single piece of sheet metal and provided with diverging 55 stiffening ribs or corrugations which extend from one of the horizontal edges of the piece of sheet metal across the same toward the opposite edge and corners thereof.
  3. A car end formed of a single piece of 60 sheet metal having formed therein a pair of vertically disposed ribs or corrugations, and a pair of diagonally disposed stiffening ribs or corrugations.
  4. A car end formed of a single piece of sheet metal having formed therein a pair of 65 vertically disposed ribs or corrugations, a pair of diagonally disposed stiffening ribs or corrugations, and a horizontally disposed stiffening rib or corrugation.
  5. A car end comprising a single piece of 70 sheet metal having formed therein pairs of diverging corrugations, and reinforcing plates applied to the sheet metal plate over said ribs or corrugations.
  6. A car end comprising a single piece of 75 sheet metal having formed therein pairs of diverging corrugations, reinforcing plates applied to the sheet metal plate over said ribs or corrugations, and a horizontally disposed stiffening rib or corrugation.
  7. A car end formed of a single piece of 80 sheet metal having formed therein a pair of diverging stiffening ribs or corrugations which extend substantially from one edge of the plate to the opposite edge thereof.
  8. A car end formed of a single piece of 85 sheet metal having formed therein a pair of diverging stiffening ribs or corrugations, and reinforcing plates fixed to said car end over said corrugations.
  9. A car end formed of a single piece of 90 sheet metal having formed therein a pair of diverging corrugations and base flanges projecting from the lower portion of said car end.
  10. A car end comprising a single piece of 95 sheet metal having formed therein a pair of vertically disposed stiffening ribs or corrugations, and also having formed therein a pair of diagonally disposed stiffening ribs or corrugations, which latter extend from the lower portions of the vertically disposed ribs or corrugations toward the upper corners of said car end.
  11. A car end composed of sheet metal and 100 having formed therein a substantially V-shaped stiffening rib or corrugation.
  12. A car end composed of sheet metal having formed therein a substantially V-shaped stiffening rib or corrugation, and reinforcing plates applied to said car end over the stiffening rib or corrugation formed therein.
  13. A car end composed of sheet metal and 105 having formed therein a pair of substantially V-shaped stiffening ribs or corrugations.
  14. A car end composed of sheet metal having formed therein a pair of substantially V-shaped stiffening ribs or corrugations, and reinforcing plates applied to said car end over said stiffening ribs or corrugations.

15. A car end constructed of sheet metal and having formed therein a substantially V-shaped reinforcing rib or corrugation, and a horizontally disposed rib or corrugation.

5 In testimony whereof I hereunto affix my

signature in the presence of two witnesses, this eighth day of January, 1918.

JOHN M. ROHLFING.
